UNITED STATES PATENT OFFICE.

ROBERT H. BUTTERS, OF ATLANTA, GEORGIA, ASSIGNOR TO THE BUTTERS-CAMP MFG. CO., A CORPORATION OF GEORGIA.

MACHINE FOR FORMING OR RENEWING AND SHARPENING THE TEETH OF GIN OR LINTER SAWS.

1,329,036.

Specification of Letters Patent. Patented Jan. 27, 1920.

Application filed April 10, 1917. Serial No. 161,902.

To all whom it may concern:

Be it known that I, ROBERT H. BUTTERS, a citizen of the United States, residing at Atlanta, in the county of Fulton and State 5 of Georgia, have invented new and useful Improvements in Machines for Forming or Renewing and Sharpening the Teeth of Gin or Linter Saws, of which the following is a specification.

10 This invention relates to a machine for forming or renewing and sharpening the teeth of gin or linter saws. It proposes a machine which is specially adapted to the practice of the method of forming or renewing gin or linter saw teeth disclosed in my U. S. Letters Patent No. 1,277,375, granted September 3, 1918.

Its principal objects are to provide a machine having a cutter for forming or renewing and sharpening the teeth wherein said cutter is positively controlled and is positive in its action; to provide a machine which shall accomplish the purposes of the ordinary filing and gumming machines, but 20 in a much more efficient manner and in a much shorter period of time; to provide a machine wherein the form of the teeth is dependent upon the operation of the forming or sharpening instrumentality in connection 25 to existing filing and gumming machines wherein the action of the sharpening instrumentalities is dependent on the form of the teeth; to provide a machine which shall produce teeth of special 30 form or construction most effectively adapted to the wearing and tearing work of linter saws; to provide a machine which shall secure exact and uniform alinement and conformity of the teeth, horizontally 35 throughout the gang; to provide a machine by means of which teeth of the requisite sharpness and strength may be provided in substantially greater number than is possible with existing machines and methods; 40 and to provide a machine adapted to form new teeth in saw blanks, to renew and sharpen the formed teeth of existing saws; and to provide saws of the ordinary types 45 with teeth of the special form or construction above referred to.

With the above and other objects and advantages in view, the invention consists in certain features of structure, combination

and relation which will appear as the description proceeds.

An embodiment of the invention is illustrated in the accompanying drawings, wherein—

Figure 1 is a front elevation of a machine in which the features of the invention 60 are incorporated;

Fig. 2 is a plan view thereof;

Fig. 3 is an end elevation thereof;

Fig. 4 is an elevation showing the end of the machine opposite to that shown in Fig. 3, certain elements of the structure appearing in Fig. 3 being omitted to avoid unnecessary repetition and for the sake of clearness;

Fig. 5 is a detail vertical sectional view 70 showing certain parts at one end of the machine in the plane 5—5 of Fig. 2, looking in the direction of the arrows;

Fig. 6 is a detail rear elevation, partly in section, showing the elements which appear 75 in Fig. 5;

Fig. 7 is a horizontal sectional view in the plane 7—7 of Fig. 5, looking downward;

Fig. 8 is a detail cross-sectional view in the plane 8—8 of Fig. 3, looking in the direction of the arrow;

Fig. 9 is a detail cross-sectional view in the plane 9—9 of Fig. 3, looking in the direction of the arrow;

Fig. 10 is a detail sectional view in the plane 10—10 of Fig. 9, looking in the direction of the arrow;

Fig. 11 is a detail sectional view of the mechanism for laterally shifting the cutter 90 heads, this figure being taken in the plane 11—11 of Fig. 1;

Fig. 12 is a detail plan view, partly in section, showing the mechanism for laterally shifting the cutter heads, and also 95 showing two of said heads;

Fig. 13 is an elevation of one of the cutter heads, looking at the inner face thereof;

Fig. 14 is a vertical longitudinal sectional view of one of the cutter heads;

Fig. 15 is a detail horizontal sectional view on the line 15—15 of Fig. 14;

Fig. 16 (Sheet 5) is a detail perspective view showing certain parts of the mechanism for controlling the operation of the 105 quadrant arms;

Fig. 17 is a detail horizontal sectional view on the line 17—17 of Fig. 4 showing a bumper block for relieving or cushioning the inward movements of the supporting arms;

Fig. 18 is a detail plan view of the cross-rail;

Fig. 19 is a detail sectional view on the line 19 of Fig. 10;

10 Fig. 20 is a detail sectional view of a pin clutch to be hereafter described;

Fig. 21 is an elevation of one member of the pin clutch shown in Fig. 20;

15 Fig. 22 is an elevation of the other member of said clutch;

Fig. 23 is a detail elevation of the pin element of said clutch;

20 Fig. 24 is a diagrammatic plan view showing the arrangement of a center rest which is preferably employed to steady the saw mandrel;

Fig. 25 is a rear elevation of the center rest;

25 Fig. 26 is a longitudinal sectional view thereto, showing also its relation to the saw mandrel;

Fig. 27 is a perspective view showing the various parts of the center rest in the relation of their assemblage;

30 Figs. 28 and 29 are diagrammatic end elevations illustrating certain operations of the machine;

Figs. 30—34^a are views illustrating dia-

35 grammatically the action of the cutter. These figures, together with Figs. 35—35^c, are drawn to a greatly exaggerated scale and have been employed because it is not possible to clearly illustrate the details of the method and the teeth in any of the preceding figures owing to the restrictions imposed by the scale to which such preceding figures are drawn;

40 Fig. 30 is a diagrammatic front or edge elevation showing one of the cutters as working simultaneously upon two saws at relatively opposite sides thereof;

Fig. 30^a is a side elevation projected in the plane 30^a—30^a of Fig. 30;

45 Fig. 30^b is a sectional plan view projected in the plane 30^b—30^b of Fig. 30;

Fig. 31 is a view similar to Fig. 30 but with the cutter omitted and showing more particularly the condition of the saws upon the completion of the first or initial cut;

50 Fig. 32 is a view similar to Fig. 30 but showing the cutter as making the second or final cut on one of the saws;

Fig. 32^a is a sectional plan view projected in the plane 32^a—32^a of Fig. 32;

55 Fig. 33 is a view showing the saws upon the completion of the operation depicted in Figs. 32 and 32^a;

Fig. 34 is a view similar to Fig. 30 but showing the cutter working on the teeth

60 next below those shown in Fig. 31;

Fig. 34^a is a side elevation projected in the plane 34^a—34^a of Fig. 34;

Fig. 35 is a fragmentary side elevation of a saw shewing the completely formed teeth;

70 Fig. 35^a is a bottom sectional plan view projected in the plane 35^a—35^b of Fig. 35;

Fig. 35^b is a normal plan view projected in the plane 35^a—35^b of Fig. 35;

Fig. 35^c is a cross-sectional view of one 75 of the teeth in the plane 35^c—35^c of Fig. 35; and

Fig. 36 is a detail perspective view showing a preferred form of cutter.

Similar characters of reference designate 80 corresponding parts throughout the several views.

Although the present invention does not relate to the structure of the teeth or the method of forming and sharpening or renewing the same, the said teeth and method forming the subjects-matter of my respective pending application Serial No. 152,894, and my said Letters Patent No. 1,277,375, the purposes and general operation of the 90 machine which constitutes the invention will doubtless be more clearly and readily understood by prefacing the detail description of the machine with a general description of the teeth and the action of the cutter in forming and sharpening or renewing the same.

The teeth.—The teeth shown are adapted for linter saws and, as finished, (Figs. 35, 35^a, 35^b and 35^c) have cutting edges A which 100 are preferably parallel as far as points B and from said points B taper to a terminal point C. The edges A and the points B and C are in the plane of the base D of the tooth; and the base D of one tooth meets 105 the upper face of the tooth next below, forming therewith an angular throat E. The upper face of each tooth has sides F inclined divergently and symmetrically from a central apex G. Inwardly of the 110 inclined faces F, the teeth have the same thickness as the saw and their sides S are co-planar with the sides of the saw. The side edges H of the inclined faces F extend parallel to the apex G and from the points 115 B to points I in the rear of the point K whereat the apex G meets the base D of the tooth next above and between which and the terminal point C the apex G extends. The points I and K may be regarded as the angles of an imaginary triangle co-planar with the base D, two sides L of which triangle connect the point K with the points I. The point K, sides L and points I constitute the angular base line of the throat E which thus has a convex V form. In practice, the distance between the terminal point of the tooth and the point K is about the same as the distance between the terminal point of an ordinary tooth and 120 125 130

its transversely straight throat. The edges A have their inner terminals at the points I and, therefore, extend for a substantial distance inwardly beyond the point K; and 5 said edges A are longer than the cutting edges of an ordinary tooth by the distance through which they extend inwardly beyond the point K. This lengthening of the cutting edges A is, however, without effect 10 in weakening the tooth at the throat owing to the facts that the tooth throughout the greater portion of its extent has the same thickness as the saw, and, hence, has an augmented amount of stock, and that the 15 integral stock within the imaginary triangle I—K—I constitutes a reinforcement for the throat while providing for the inward extension of the edges A beyond the transverse line in which the point K is located. Stated otherwise, the base of each 20 tooth is undercut at the throat to provide for inward extensions of the cutting edges and for an integral reinforcement projecting outward beyond the inner terminals of 25 the cutting edges.

Fig. 35^a shows in plan the outline of the base of the tooth and the integral reinforcement I—K—I at the throat, providing for the undercutting of the base at the inner end 30 thereof and the inward extension or prolongation of the cutting edges A.

Fig. 35^b shows, in plan, the outline of the upper face of the tooth and the integral reinforcement I—K—I.

35 Fig. 35^c shows the tooth in cross-section in a plane perpendicular to the apex G and between the points B and K. From this figure it will be apparent that the portion of the tooth between the sides S and which constitutes, by far, the greater part of the 40 material of the tooth, is of the same thickness as the saw, and, hence, that the tooth, notwithstanding the inward prolongation of the cutting edges and the undercutting of the 45 base at the front, has its stock greatly augmented, as compared with the stock of an ordinary tooth. It follows that the teeth may be cut substantially finer, without undue sacrifice of strength or reduction of the 50 length of the cutting edges than is possible with the constructions heretofore existing.

The teeth have a closer and more efficient working fit between the bars of the usual gin or linter grid and their cutting edges 55 work closer to the seed, while the liability of cutting or injuring the seed is greatly diminished. The actual point of the tooth may be regarded as the pyramid of triangular cross section whose imaginary base extends 60 from the points B in a plane perpendicular to the apex G. This pyramid, it will be noted, has its lateral faces comparatively short but its base comparatively extensive along all of its sides, from which it follows 65 that the terminal point of the tooth has

much greater strength than the terminal point of the ordinary tooth which is a pyramid of rectangular cross section throughout its extent with comparatively long lateral faces and with comparatively short lines 70 for any imaginary base located at a much greater distance from the terminal apex than the base B—G—B of the triangular pyramid which constitutes the point of the present tooth.

75 *The method.*—The method is applicable to the saws or saw blanks as assembled in gangs on the usual mandrel of the gin or linter. Under the practice heretofore existing, the teeth are first formed by a punching die 80 and the saws are thereafter sharpened by side filers, after which they are assembled as a gang. In the practice of the present method, as applied to saw blanks, the blanks may be first assembled as a gang and there- 85 after the teeth formed therein. The method contemplates a cutter of special character to form the teeth by successive operations performed first at one, and then at the opposite, side of the saw.

90 This cutter is preferably of the well known form shown in Fig. 36 and which is known in the mechanical trades as an "angular bevel cutter," but other forms of cutters adapted to the invention may be employed, if desired. The cutter, as 1, is disclosed in a form which is adapted to the production of teeth of the structure shown in Figs. 35, 35^a, 35^b and 35^c and has a suitable number, e. g., eight, of cutting teeth 2, which, as 100 shown and preferred, have substantially radially disposed cutting edges 3 terminating at points 4 from which the outer edges of the teeth recede to points inwardly of the imaginary circle wherein the 105 points 4 lie. The upper faces of the teeth are in planes inclined at a slight angle downwardly from the common plane wherein the edges 3 lie and the under faces of the teeth have a regular and uniform bevel whereby 110 the lower cutting edges 3^a extend at an acute angle inward and downward from the edges 3. The cutter, as will be hereafter described in detail, is mounted upon a spindle, and, in use, is rotated at a rapid rate.

115 Figs. 30—34^a of the drawings show the cutter as working in relation to three saw blanks of a gang. The operation, however, is the same whether the cutter work on saw blanks for the purpose of forming new 120 teeth therein, on formed saws of the ordinary types for the purpose of cutting teeth therein of the special type which the invention provides for, or on formed saws having teeth of the construction herein described for 125 the purpose of renewing and sharpening them.

130 As above stated, the cutter performs two successive operations on a saw in the formation of a tooth, one operation being at one

side of the saw, and the other operation being at the other side of the saw.

The three saw blanks are designated X, Y and Z. Fig. 30 shows the cutter working simultaneously at the right side of the blank X at the left side of the blank Y. The cutter commences its operation at a point on the periphery of the blank and is fed inward by the means provided therefor through a distance necessary to form the tooth of the length contemplated. In Fig. 30^a the cutter is shown at the limit of its inward movement and the work on one side of the blank X as completed. Fig. 31 shows the cuts made in the blanks X and Y when the cutter works in relation to said blanks, as shown in Figs. 30 and 30^a. In both blanks X and Y the cutter has with its cutting edges 3 formed the base D of the next preceding tooth and has undercut said base at one side thereof, at the right side of the blank X and at the left side of the blank Y, as best shown in Fig. 30^b. In both cases, the cutter has made a substantially V-shaped notch in the blank, and of which the base D forms one wall. The other wall of the notch is formed by the cutting edges 3^a and is inclined laterally, its inclination being downward toward the right in the blank X and downward toward the left in the blank Y. A portion of the surface of the laterally inclined wall of each notch constitutes one of the inclined sides F of the upper face of the tooth. Fig. 32 shows the cutter as working simultaneously upon the blanks Y and Z, at the right side of the blank Y and the left side of the blank Z. The cutter forms a notch in the blank Z exactly similar to the notch previously formed in the blank Y, as shown in Fig. 31. In its operation on the blank Y in Fig. 32 the cutter completes the tooth except for the formation of the base thereof, that is to say, in working on the right side of the blank Y the cutter completes the under cutting of the base of the next preceding tooth, as shown in Fig. 32^a and cuts away one side of the transversely inclined wall of the notch whereby the said wall has an inverted V-shaped cross-section and is accordingly formed with the apex G and inclined sides F, as shown in Figs. 33 and 32^a. In Fig. 34 the cutter is shown as working in the same relation as in Fig. 30 upon the blanks X and Y but as forming the teeth next below the teeth formed by the operation depicted in Fig. 30. The action of the cutter in the relation shown in Fig. 34 is exactly the same as in Fig. 30. That is to say, the cutter forms the base of the next preceding tooth and cuts a V-shaped notch of which said base forms one wall. It is to be observed, however, that the plane of the base includes the lower or outer terminal point of the apex G, as shown in the case of

the blank Y in Fig. 33, whereby the outer end of the base is triangular and the point of the tooth is of triangular pyramidal form. This is very clearly illustrated in Figs. 34 and 34^a showing a completed tooth T and below it a half-finished tooth T'. It will be observed that the base D of the tooth T is cut in a plane in which the lower or outer end of the apex G, as formed prior to the cutting of the tooth next below, lies. It will be understood that all of the teeth are formed similarly to the tooth T shown in Figs. 34 and 34^a, and that the showing of the cutter as working only at the right side of the blank X and at the left side of the blank Z has been adopted merely as a matter of convenience to illustrate the operation of the cutter at relatively opposite sides of the blank. It is, of course, obvious that the teeth of the blank X requires for their completion operations of the cutter at the left side of said blank similar to the operations shown in connection with the blank Z, and that the teeth of the blank Z require for their completion operations of the cutter at the right side of said blank similar to the operations shown in connection with the blank X. When the cutter working at one side of the blank has formed a notch therein, it is moved beyond the periphery of the blank and the blank is then shifted about its center as an axis of rotation through the distance of a tooth whereby the cutter may repeat the operation in connection with the formation of the next lowermost tooth. In working on the old teeth of formed saws, the principles of operation are the same. In such cases, if the saws be of the types heretofore existing, the teeth are entirely recut, i. e., the old teeth are cut away and new teeth are formed; and if the saws be provided with teeth of the construction herein described, the teeth are renewed and brought to their original form, and, in the case of linter teeth, to their original degree of sharpness, whereby, in all cases, the teeth are maintained uniform and in the most efficient condition, although the actual cutting involved in such renewal of the teeth may be comparatively slight.

In all cases, the action of the cutter is positive since it is upon the stock of the teeth rather than upon the mere surfaces thereof, as in the case of the filers and gummers of the ordinary sharpening machines, that the cutter works. Hence, the action of the cutter is independent of the condition or alinement of the teeth transversely of the gang, and such alinement will be perfectly and uniformly maintained.

The present invention proposes a machine for carrying out the method and cutting teeth of the character above described. The machine disclosed may be termed a "multiple-head" machine in that it embodies a

plurality of heads, each provided with a cutter operating in relation to a definite group of saws of the gang.

The instrumentalities of the machine disclosed, broadly stated, are the cutter heads and their movable supporting means, means for reciprocating or oscillating the cutter heads in connection with the tooth-forming operations, means for feeding the saws or saw blanks through the distance of a tooth in relation to the normal reciprocatory or oscillatory movements of the cutter heads, means for effecting lateral shifting movements of the cutter heads in connection with the completion of the work of the cutters on one saw and the inception of their work on an adjacent saw, and means for controlling the direction of lateral movement of the cutter heads whereby said heads may be moved from right to left in connection with their work on one gang of saws, and from left to right in connection with their work on the next gang of saws which is placed in the machine.

The cutter heads.—The number of cutter heads employed is dependent upon considerations of practice and choice and, hence, may be varied as conditions may require. Obviously, the greater the number of cutter heads, the shorter will be the time required for the work on a gang of saws. It is contemplated, however, that each cutter shall complete the teeth of four saws. Thus, for inter gangs, which usually comprise one hundred and six saws, it is proposed to provide twenty-seven cutter heads. In such a case, the first cutter will do all of the work on the first three saws and half of the work on the fourth saw, and the last cutter will do half of the work on the third saw from the adjacent end of the gang and all of the work on the last two saws, while each of the remaining twenty-five cutters will work on five saws, doing all of the work on the three intermediate saws of the group and half of the work on each of the two end saws of the group. Thus, the two end saws of each group will be common to the adjacent groups whereby the work on one side of one of said end saws will be done by one cutter and the work on the opposite side thereof will be done by the next adjacent cutter. For example, the second cutter will commence its work upon one side of the fourth saw and the first cutter will complete its work on the opposite side of the fourth saw, the said fourth saw being thus completed by the operation at opposite sides thereof of two adjacent cutters. In like manner, the eighth saw is completed by the operation at opposite sides thereof of the second and third cutters, and so on throughout the gang. It is essentially practical and in the interests of economy of time and simplicity of construction and operation for

each cutter to work simultaneously upon relatively opposite sides of two adjacent saws, as clearly shown by the diagrams of Figs. 30—34^a, and the machine, as herein disclosed and preferred, is constructed with such a scheme of operation in view.

To avoid duplication and simplify the disclosure of the drawings, but two of the cutter heads are shown in the views of the machine as assembled, it being understood that the remaining cutter heads are similar in arrangement and construction to the two disclosed. The cutter heads 5 (Figs. 1 and 2) each comprise (Figs. 13, 14 and 15) a casing 6 which provides a bearing for a spindle 7 extending through the same and projecting beyond its upper and lower faces. The casing 6 has formed therewith at its lower end a step block 8 between which the lower end of the casing proper is a clearance 9. The cutter 1 operates in the clearance 9 and is mounted on the spindle 7 by which it is rotated, the said spindle for this purpose having a square terminal projection 10 at its lower end which engages in a central square opening 11 of the cutter 1 (Fig. 36). The block 8 carries a hard steel wear plate 12 against which the cutter and the lower end of the spindle 7 rotates. The casing 6 is closed at its upper end by a suitable cap 13 and the spindle 7 has near its upper end a circumscribing groove 14 in which the end of a retaining screw carried by the cap 13 engages.

In the operation of the machine, the spindles 7 and therewith the cutters 1 are continuously rotated, the gearing for this purpose preferably comprising a spiral gear 15 mounted upon each spindle 7 and a spiral gear 16, companion to each gear 15, and mounted upon a horizontal drive shaft 17. The casing 6 has at a suitable elevation thereon an opening which extends between its front and rear faces and the gear 15 is set into said opening and is keyed upon a reduced portion 7^a of the spindle 7, the said reduced portion extending to the lower end of said spindle and providing an annular shoulder 7^b just above and which rests upon the gear 15. By reason of the reduced portion 7^a, the spindle 7 may be disconnected from the gear 15 and removed from the casing 6 by lifting it upward from said casing, the cap 13 having been, of course, previously removed.

The gears 16 have hub extensions 18 which are journaled in suitable bearings 19 secured against the outer faces, (*i. e.* the faces remote from the saws), of the casings 6 by retaining bolts 20. The bolts 20 also serve to secure against the inner faces, (*i. e.* the faces adjacent the saws) of the casings 6 guard plates 21 which close the openings in which the gears 15 are arranged and protect said gears from dust.

The lower portion of each casing 6 is provided with two narrow slots or recesses 22 into which the two saws upon which the cutter 1 simultaneously operates as above 5 explained project, the lateral walls of said slots rigidly bracing the saws against lateral bending play incident to the operation of the cutter.

The means of support for the saws and the cutter heads.—The machine includes a base or bed 24 (Figs. 1, 2, 3, 24 and 25) which is to be secured to the floor or other support by lag screws, and which carries at its ends upright standards 25 having at their upper 15 ends bearings 26 of the removable cap block type. The saw mandrel M is supported by the standards 25 and at one end has a direct engagement in the bearing 26. At its other end, said mandrel projects through the hub 20 extension 27 of a gear 28 which is located adjacent the outer face of the adjacent standard 25 and is an element of the saw feeding mechanism. The said hub extension 27 is made fast to the mandrel M by a screw 25 fastening and is journaled in the adjacent bearing 26.

For the support of the cutter heads, the machine includes arms 29 and 30 arranged adjacent the ends of the base 24 and pivotally movable about end trunnions or studs 31 (Fig. 1) projecting laterally from said base, said arms each having at their lower ends a sleeve 32 loosely surrounding the stud 31.

35 The cutter heads 5 are slidably mounted upon a horizontal cross-rail 33 (Figs. 1, 9 and 18), arranged transversely of the machine. The rail 33 is directly supported by the arms 29 and 30, and for this purpose 40 has cylindrical terminal extensions 34 and 35 which are secured in clamp boxes 36 at the upper ends of said arms. The rail 33 incloses the shaft 17 and the spiral gears 16 and its cylindrical terminal extensions 34 and 35 provide bearings for the ends of 45 said shaft which, beyond said bearings, is provided with end retaining collars 37.

Since the rail 33 supports the cutter heads 5, the shaft 17 is supported not only by and 50 at the ends of said rail, but also at regular intervals throughout its extent, such intervallic support being provided, as is obvious, by the spiral gears 16 through whose hub extensions 18 said shaft projects.

55 That portion of the rail 33 upon which the cutter heads are slidably mounted has a C-shaped or semi-circular cross-section (Fig. 14) which is preferably provided with a central longitudinal bracing rib 33^a. The 60 outer faces of the cutter heads lie uniformly against the adjacent faces of the rail 33; and said cutter heads are provided at their upper and lower ends with forward or outward extensions 38 and 39. The extension 65 38 is provided with an internal recess 40

and with a depending shoulder 41 adjacent said recess and the extension 39 is provided with an internal recess 42 and with a shoulder 43 adjacent said recess. The rail 33 is formed along its upper edge with a continuous rib 44 which fits closely in the recesses 40 of the several cutter heads and with a continuous groove 45 into which the shoulders 41 of the cutter heads project; and said rail is formed along its lower edge with 75 a continuous rib 46 which fits into the recesses 42 of the several cutter heads and over which the shoulders 43 of said heads engage. To insure the alinement of the cutter heads, as also to prevent wear, hard 80 steel gibs 47 are arranged in the recesses 40 in contact with the upper face of the rib 44. Said gibs are movable with the cutter heads, and for this purpose are suitably engaged by the lower ends of screws 48 threaded in 85 the extensions 38.

By virtue of the engagement of the ribs 44 and 46 in the recesses 40 and 42, the cutter heads will be freely slideable lengthwise of the cross-rail 33 but will be rigid 90 with said rail in planes parallel to the planes of the saws or the planes of oscillatory movement of the arms 29 and 30.

The bearings 19 for the hub extensions 18 of the gears 16 are arranged at each side 95 of the said gears; and the key 49 which forms a connection between said gears and the shaft 17 extends continuously along said shaft. It follows that the gears 16 will be slid along the shaft 17 by the cutter heads, 100 as said heads are, in turn, slid along the rail 33.

The cross-rail terminal extensions 34 and 35 have bearings in the clamp boxes 36 of the arms 29 and 30; and, upon loosening 105 the bolts of said clamp boxes, the cross-rail may be turned pivotally about its central longitudinal axis, its terminal extensions functioning as trunnions. When gangs of saws are to be removed from the machine, 110 the cross-rail is turned upward and outward in order to bring the cutter heads into positions well beyond the peripheries of the saws in order that they may present no obstruction to the saws in connection with the 115 removal of the gang from the machine; and, for a similar purpose, the cross-rail is left in the position into which it is thus turned until the gang of saws or saw blanks next to be operated upon is placed in the machine, 120 after which the cross-rail, and therewith the cutter heads, are restored to their normal positions and the cross-rail is secured by tightening the bolts of the clamp boxes 36.

The mechanism for normally reciprocating or vibrating the cutter heads.—In the 125 operation of the cutters on the saws, the cutters, operating simultaneously, each commence the formation of a tooth at the periphery of the saw and are gradually 130

- 10 moved inward until the notch which provides the base of one tooth and the upper surface of the next succeeding tooth, has been cut to the prescribed length, after 5 which they are moved outward to a position slightly beyond the peripheries of the saws whereby the saws may be rotated by the saw feeding mechanism to be hereafter described.
- 10 The arms 29 and 30 are supported by feed arms 50 (Fig. 5) which are pivoted on the studs 31 and are arranged adjacent the inner sides of said arms 29 and 30. The arms 50 are normally held in fixed positions, and the 15 arms 29 and 30 are supported and operated, *i. e.* continuously vibrated, therefrom by cams 51 mounted upon a continuously driven cam shaft 52 for which the arms 29 and 30 provide end bearings. The feed arms 50 20 carry at their upper ends hard steel rollers 53 against which the cams 51 work. The arms 29 and 30 tend to move outward about their pivots 31 by gravity and their outward movement is limited and controlled by 25 the engagement of the cams 51 against the rollers 53. Said cams rotate in the direction of the arrow (Fig. 5) and as their highest points approach the rollers 53 effect an inward movement of the arms 29 and 30, and 30 therewith, of the cutter heads and cutters. During such inward movement the cutters accomplish their work. The cams drop abruptly beyond their highest points whereby when said points pass beyond the rollers 53, 35 the arms 29 and 30, and therewith the cutter heads and cutters, will move outward by gravity at a relatively rapid rate to positions wherein the cutters are just beyond the peripheries of the saws.
- 40 It is preferred to provide bumper or cushion means for engagement by the arms 29 and 30 in connection with their inward movement, *i. e.* their movement toward the saws, and for this purpose the feed arms 50 45 are provided with blocks 54 carrying elastic rubber bumper pieces 55, and having at one side thereof shanks 56 which are suitably secured in openings 57 in said feed arms. The arms 29 and 30 have a channeled cross- 50 section (Fig. 17) and the block 54 projects between the side flanges thereof and is engaged by an abutment lug 58 formed with or secured to each arm.
- 55 The feed arms 50 are, in effect, functional parts of quadrant arms 59 by which they are supported in their normal positions. The quadrant arms 59 which are also pivotally mounted on the studs 31 and are arranged between the feed arms 50 and the sides of 60 the base 24 are elements of the mechanism for positioning the cutter heads and are normally and positively held stationary by a mechanism to be hereafter described. The feed arms 50 are provided separately from

the arms 59 in lieu of being formed integral or rigid therewith in order that they may be adjusted to vary the positions of the cutters relatively to the peripheries of the saws (in compensating for variations in diameter among saws of different types or 70 for different kinds of machines); and for this purpose said feed arms and said quadrant arms are provided with laterally projecting swiveled blocks 60 and 61 and a screw stem 62 has its end swiveled in the 75 block 60 of each feed arm and is threaded through the block 61 of the adjacent quadrant arm, the said stem thus forming a means of connection between the quadrant arm and the feed arm whereby the latter is 80 supported from the former. Obviously, by turning the stem 62 in either direction, the feed arm may be moved inward or outward to vary the positions of the cutters relative to the peripheries of the saws. To 85 secure uniformity of adjustment and absolute alinement of the cutters, it is preferred that the stem 62 should be operated simultaneously and in conjunction with one another, and for this purpose, said stems are, 90 as shown in Fig. 1, provided with sprocket wheels 63 over which is passed a connecting endless chain 64 whereby a turning movement of either of the stems 62 will be transmitted to the other stem. 95

The saw feeding mechanism.—During the short interval in which the cutters are located just beyond the peripheries of the saws, the saws are moved through the distance of a tooth whereby on the next inward movement of the cutters a notch will be cut the requisite distance below the notch cut on the preceding inward movement.

The gear 28 whose hub is made fast to the saw mandrel M is engaged by a gear 65 105 (Figs. 3 and 7) mounted on a post or stem 64', which projects laterally from the adjacent standard 25. The gear 64 is connected to or formed with a ratchet wheel 66 which, together with its operating lever 67, is also 110 mounted on said post. The lever 67 carries a pawl 68 for engagement with the ratchet wheel 66 and the free end of said lever projects under the cam shaft 52 and is engaged by a cam 69 (Fig. 5) on said shaft. 115 The lever 67 is held against the cam 69 by a supporting spring 70 and said cam depresses the free end of said lever and thereby effects a movement of the ratchet wheel 66 through the distance of a tooth, during 120 the interval in which the cutter heads lie just beyond the peripheries of the saws. Obviously, the number of ratchet teeth on the wheel 66 and the ratio of the gears 64 and 28 is selected with reference to the number 125 of teeth with which each saw is, or is to be, provided; and in case it is desired to change the number of teeth on a saw, a ratchet

wheel, whose teeth are selected with regard to the number of saw teeth contemplated, may be substituted.

The cutter head positioning mechanism.—
5 When the cutters have completed their work at one side of the saw, they are automatically shifted to a position wherein they work upon the opposite side of the saw and upon the adjacent side of the next saw.
10 This shifting of the cutters is accomplished in three phases, the first involving a movement of the cutters wholly beyond the peripheries of the saws and to a substantially greater distance beyond said peripheries
15 than is normally provided for by the cams 51, the second involving a horizontal or transverse movement of the cutters, and the third involving the return movement of the cutters into their normal operative positions
20 relatively to the saws.

For the first and third phases of the operation of shifting the cutters, the quadrant arms 59 are employed. The arms 59 are, in point of function, elements for moving the supporting arms 29 and 30 and therewith the cutter heads from and back to their normal operative positions. In the present embodiment they are of quadrant form and, as a matter of convenience, will hereafter be referred to as "quadrants." Said quadrants are operated in their movements and are normally held stationary by eccentrics 71 which work in rectangular slots 72 formed in the quadrants (Figs. 3, 4, 28 and 35 29). The eccentrics 71 are fast on a shaft 73 which extends transversely of the machine and for which end bearings 74 (Figs. 1 and 6) are provided by the bed 24 and the standards 25. Upon the completion of the work of a cutter at one side of a saw, the eccentrics 71 are rotated through one revolution to effect an outward movement of the quadrants 59 and a return movement of said quadrants to their normal positions in which they are held stationary by said eccentrics. It will be apparent that the feed arms 50 and therewith the arms 29 and 30 and the cutter heads participate in these outward and return movements of the quadrants 59.

The shaft 73 is normally stationary but is rotated to operate the quadrants 59 from a sprocket wheel 75 mounted loose on the end of said shaft which adjoins the arms 29 and 55 continuously rotated by gearing to be hereafter described. The rotation of the shaft 73 by the sprocket wheel 75 is controlled by a clutch 76 (Figs. 6 and 20-23) preferably of the type known in the mechanical trades 60 as a "pin clutch." One member 77 of this clutch is secured to or formed with the hub of the sprocket wheel 75 and the other member 78 is suitably secured to or formed with the adjacent eccentric 71. The member 78 65 and its companion eccentric 71 are formed

with a socket 78^a for a spring-pressed laterally movable connecting pin 79, and the member 77 has a reduced hub extension which forms the base of an annular groove 80 intermediate the clutch members and is 70 provided with a transverse recess 77^a. A lever 81 has its free end normally held in the groove 80 in a position to hold the pin 79 retracted or wholly within the socket 78^a.

The laterally movable pin 79 has an enlarged head 79^a provided with a bevel or cam face 79^b, said head normally occupying a conforming enlarged end 78^b of the socket 78^a; and that end of the lever 81 which engages in the groove 80 has a corresponding lateral bevel 81^a. In the operation of the pin clutch, the lever 81 is moved to release the pin 79 which, by means of the spring acting thereon, is thereupon snapped across the groove 80, its shank engaging in the 85 recess 77^a, which normally alines with said pin, and its enlarged head 79^a whose thickness is greater than the width of the groove 80 lying partly in said groove and partly in the conforming socket end 78^b. Thereupon, the sprocket wheel 75 rotates the shaft 73 and during such rotation the lever 81 is restored to its normal position with its end in the groove 80 whereby the bevel face 79^b of the pin 79 engages the bevel face 81^a of the lever 81 with the result that said lever effects the retraction of said pin and its disengagement from the member 77, thereby interrupting the rotation of the shaft 73.

The lever 81 is pendant from a rock shaft 82 journaled in a bearing 83 formed with the quadrant 59 by which said lever is carried; and the lower end of said lever is held in the groove 80 by a suitable spring 84. 105 The operation of the lever 81 is controlled by the gear 28 through connections which are preferably as follows: The shaft 82 carries an arm 85 for engagement by a plunger 86 which is operated by a laterally projecting pin 87 on the gear 28 (Figs. 5, 6, 8 and 16). The plunger 86 is mounted for sliding and pivotal movement and is supported by a rock shaft 88 journaled in the adjacent standard 25. At the outer face of 110 said standard, the shaft 88 is formed with a rectangular guide block 89 and beyond said guide block with a retaining head 90. The plunger 86 is formed with a rectangular slot 91 in which the block 89 is disposed whereby said plunger may slide lengthwise of said block, and the head 90 engages over the outer face of the plunger 86 to prevent lateral displacement thereof from the shaft 88. The plunger 86 is held in a normally elevated position by a spring 92 arranged between the upper face of the block 89 and the upper wall of the slot 91. The shaft 88 is held in its normal position by a torsion spring 93 surrounding its inner end portion. 130

The plunger 86 has a pointed lower end 94; and the arm 85 has projections 95 and 96 for coöperation with the pointed plunger end 94. The plunger engages the projection 95 to effect a turning movement of the shaft 82 and a disengagement of the lever 81 from the groove 80, and thereafter the projection 96 engages the lower end of the plunger to turn the latter about the shaft 88 as a pivotal axis whereby the upper end of the plunger will be moved beyond the pin 87 to avoid interference with the movement of the gear 28. The upper corner of the plunger over which the pin 87 ultimately passes in connection with the rotation of the gear 28 is rounded as at 97 to facilitate the movement of the pin 87 past the plunger.

The operation of the mechanism just described is as follows: When the gear 28 is rotated to provide for the cutting of the final tooth in the saws, the pin 87 moves the plunger downward along the block 89 as a guide and against the pressure of the spring 92. In such downward movement, the pointed end 94 of the plunger engages the projection 95 and rocks the shaft 82 to effect the withdrawal of the lever 81 from the groove 80, and shortly thereafter the projection 96 by its engagement with said pointed end 94 turns the plunger about the shaft 88 as an axis whereby the upper end of the plunger passes beyond the pin 87 to permit the spring 92 to move the plunger back past the pin and into its normal elevated position. Upon the withdrawal of the lever 81 from the groove 80, the pin clutch 76 operates automatically, as above explained, whereby the shaft 73 is driven from the sprocket 75. At such time, the quadrants 59 are moved outward and then inward back to their normal position. When the plunger 86 is returned by the spring 92 to its normal elevated position the spring 84 moves the lever 81 back into its normal position with its lower end within the groove 80; these operations take place shortly after the shaft 73 commences its rotation, with the result that, as the elements of the pin clutch come into their normal positions, the pin 79 will be retracted or disengaged from the member 77 and the rotation of the shaft 73 will be interrupted, as previously explained.

It is essential that the saw feeding mechanism should be rendered inoperative during the movement of the quadrants 59; and for this purpose, the pawl 68 is of special form and the spring 98 which holds said pawl against the teeth of the ratchet wheel 66 is carried by the adjacent quadrant 59. The pawl 68 is provided with a depending arm 99, which, in the normal position of the adjacent quadrant 59, has its lower end within a recess 100 formed in the upper face of said quadrant. As the quadrant is moved

outward, it carries with it the spring 98, thereby moving this spring away from the arm 99 of the pawl 68 and at the same time, the rear wall of the recess 100, acting upon the lower end of the arm 99, positively disengages the pawl from the ratchet wheel 66. When the quadrant 59 is returned to its normal position, the lower end of the arm 99 enters the recess 100 and the spring 98 effects the engagement of the pawl with the ratchet wheel 66.

To prevent any relative backward movement or play of the ratchet wheel 66 during the movement of the quadrants 59, as an incident of the restoration of the plunger 86 and the lever 81 to their normal position and in consequence of the lateral pressure of said plunger against the pin 87, a locking or retaining pawl 101 may be provided for engagement with said ratchet wheel.

The second phase of the operation of positioning the cutter heads involves the lateral movement of a shifting head 102 (Figs. 11 and 12). The cutter heads are made fast to upper and lower shifting rods 103 which are actuated by the head 102. The outward extensions 38 and 39 of the cutter heads (Figs. 14 and 15) are provided with transverse openings through which the rods 103 extend and the cutter heads are made fast to these rods by set screws 104 threaded through said extensions. The shifting head 102 is, in each operation thereof, given a complete reciprocation and effects a lateral movement of the cutter heads in one direction of its reciprocating movement. For this purpose, the shifting head is provided with openings through which the rods 103 project, and said rods are formed adjacent said shifting head with ratchet teeth 105 for engagement by pawls 106 carried by the shifting head, the said pawls acting on said teeth to move the rods 103 with the shifting head during its movement in one direction and riding idly over said teeth during the return movement of said head.

In the example previously suggested, where twenty-seven cutter heads are employed for a gang containing one hundred and six saws, said cutter heads will have four different operative positions relatively to the gang and will be shifted three times, in the same direction, in connection with the completion of the work on all the saws of the gang.

As previously stated, it is proposed that the cutter heads shall be shifted in one direction in connection with their work on one gang of saws and in the opposite direction in connection with their work on the next gang of saws, an advantage being thereby secured in that no resetting of said heads is necessary. For this purpose, the pawls 106 are of double form, being each provided with oppositely located teeth 107 and 108;

and means is provided whereby said pawls may be adjusted to effect movements of the cutter heads by the agency of either of their teeth. The pawls are mounted upon central 5 pivot pins 109 and have tail extensions 110 which are connected by a rod 111. For the adjustment of the pawls 106 a lever 112 is provided, said lever being pivotally mounted upon the upper face of the shifting head 102 by means of the upper pin 109. The lever 112 has a transversely elongated tail extension 113 at the forward or outer side of the shifting head and said extension has, in its under face, an arcuate channel or recess 114 into which the extended upper end 15 of the connecting rod 111 projects. The said channel or recess 114 incloses springs 115 and 116 which act on the rod 111 at opposite sides thereof. The lever 112 at its inner or rear end overhangs the shifting head 102 and is provided with a vertically movable spring-held locking pin 117 for engagement in any one of three recesses 118, 119 and 120 in the upper face of the shifting head. The adjustment of the pawls 106 is effected by the lever 112. As shown in Fig. 12, said lever is in a position in which its pin 117 is engaged in the recess 118 and the spring 115 is under compression and acts 20 on the rod 111 to position the pawls 106 whereby their teeth 107 engage the ratchet teeth 105 of the rods 103. To reverse the direction of the shifting movement of the cutter heads, the lever 112 is moved from 25 the position in which it is shown to the reverse or opposite position wherein its latching pin 117 engages in the recess 120. In such a reverse position the spring 116 will be under compression and will position the 30 pawls 106 whereby their teeth 108 will engage the ratchet teeth 105 of the rods 103. If, for any reason, it should be found desirable, the pawls 106 may be held in a disengaged position, for which purpose the 35 lever 112 is moved to an intermediate or neutral position wherein it is held by the engagement of its latching pin 117 in the recess 119 and wherein both of the springs 115 and 116 act with equal pressure on the pawl 40 connecting rod 111. The number of teeth 105 is selected to accord with the number of shifting movements of the cutter heads necessary to complete the operation on a gang of saws and, while an excess number 45 of teeth may be provided, if desired, it is only necessary to provide as the total number of such teeth the sum of the number of shifting movements plus the number of teeth spanned by the pawl teeth 107 and 108. 50 The head 102 surrounds and is movable lengthwise of a cylindrical cam 121 by which it is operated. The cam 121 is rotated at periods of the operation of the machine and in the instant embodiment is provided throughout its circumference with a

double cam groove 122 and has its operative movement through half a revolution. The head 102 is provided at diametrically opposite points with anti-friction balls 123 which form operative connections between said 70 head and the cam 121 and are held engaged in the groove 122 by backing plugs 124. When the cam 121 is rotated through half a revolution, it effects a complete reciprocation of the head 122, *i. e.*, a movement of 75 said head from and back to its normal position.

The cam 121 is formed as a part of or secured to a sleeve 125; and the cylindrical terminal extension 34 of the cross-rail 33 80 projects through said cam and said sleeve and provides an elongated bearing therefor. The sleeve 125 carries at its end remote from the cam 121 a gear 126 which is an element of the operating mechanism for said cam. 85 The sleeve 125 with its cam 121 and gear 126 is mounted upon the cylindrical terminal extension 34 of the cross-rail between the cross-rail supporting arm 29 and the shoulder provided by the adjacent end of 90 the C-shaped cutter-head-carrying part of the cross-rail.

The gear 126 (Figs. 1, 2 and 9) is engaged at its under side by a gear 127 loosely mounted upon a continuously driven shaft 128 which forms an element of the gearing for driving the cam shaft 52 and has its bearing in the arm 29. The rotation of the gear 127 with the shaft 128 is controlled by a pin clutch 129 similar to the pin clutch 76 100 previously described and shown in detail in Figs. 9 and 10. The pin clutch 129 includes a member 130 formed with or secured to the gear 127 and loose on the shaft 128 and a member 131 fast on the shaft 128 and between which and the member 130 there is a peripheral groove 132. The member 131 carries a spring-pressed connecting pin 133, which, in the operation of the clutch, engages in a recess 134 in the member 130. 110 The pin 133 is normally held retracted and disengaged from the recess 134 by the end of a lever 135 which normally engages in the groove 132. The said pin 133 and co-acting end of the lever 135 have conforming 115 cam or bevel faces whereby, assuming that the end of the lever 135 is in the groove 132, the pin 133 will, as the rotation of the clutch member 131 is continued, impinge the end of the lever 125 and be moved laterally 120 thereby into its normal retracted position.

The lever 135 is mounted on a rock shaft 136 which is operated in connection with the outward movement of the quadrants 59 and which has a bearing 137 on the cross-rail 125 supporting arm 29. The shaft 136 is moved to and held in a normal position by a torsion spring 138 surrounding one end thereof and at its other end carries a trip arm 139. For the operation of said shaft, there is pro- 130

vided a stationary block 140 (Figs. 3, 10 and 19) which is engaged by the trip arm 139 as the arm approaches the limit of its outward movement in participation with the 5 outward movement of the quadrants 59. The block 140 is carried by a bracket 141 secured to the bed 24 and is adjustable in order that its position may be made to accord with changes in the normal relative 10 positions of the arm 29 in consequence of an adjustment thereof by means of the adjusting screws 62 which connect the quadrants 59 and feed arms 50, as described. To provide for an adjustment of the block 140, 15 the end of the bracket 141 which carries said block is formed with a slot 142 and the block 140 has at one side thereof a rectangular lug 143 which has a conformable fit in said slot and beyond said lug is provided with a 20 threaded stem 144 carrying a clamp nut 145.

As the arm 29 approaches the outward limit of its movement with the quadrants 59, the trip arm 139 engages the block 140, thereby rocking the shaft 136 to effect the 25 disengagement of the lever 135 from the groove 132, as clearly shown in Fig. 10. At such time, the pin clutch operates automatically whereby the gear 127 is rotated with the shaft 128. The ratio of the gears 30 127 and 126 is 1-2 and in one revolution of the gear 127 the gear 126 will, therefore, make a half revolution, during which it effects the operation of the cam 121, as above described. The operation of the pin clutch 35 129 is continued through only a single revolution, since, during its operation, the trip arm 134 is moved away from the block 140 and the shaft 128 is restored to its normal position by the spring 138, thereby moving 40 the arm 135 back into the groove 132 with a consequent retraction of the pin 133 by said arm upon the completion of one revolution of the clutch member 130.

The operation of the cam 121 is effected 45 somewhat rapidly but seasonably during the return movement of the quadrants 59 whereby when said quadrants complete their return movement, the cutters will be positioned in operative relation to the saws and 50 saw faces next succeeding those upon which they were working at the inception of the forward or outward movement of said quadrants.

The gearing.—The shaft 17 which operates the cutter-carrying spindles 7 through 55 the gears 16 and 15 is the main drive shaft of the machine and carries at the end thereof adjacent the arm 30 cone pulleys 146 by which it is belted to pulleys 147 supported 60 by the bed 24 and driven from a counter-shaft (not shown) by a belt trained over a drive pulley 148. The shaft 17 at the end thereof adjacent the arm 29 carries a gear 149 in mesh with a gear 150 on the intermediate shaft 128. The shaft 128 drives the

cam shaft 52 through the agency of a back gear comprising large and small pinions 151 and 152 on the shaft 128, small and large pinions 153 and 154 on the shaft 52 and the usual back gear pin 155 whereby the shaft 70 52 may be driven from either of the pinions 153 and 154. This back gear is provided in order that the speed of the machine may be adapted to the character of the work in hand. Thus, a greater time will be required 75 for cutting new teeth in saw blanks than for renewing the teeth of formed saws; and consequently, for the purpose of cutting new teeth, the machine will be driven by pinions 152 and 154, at a speed slower than its 80 speed when driven for the purpose of renewing formed teeth, by the pinions 151 and 153. The cam shaft 52 has an extended end which carries a sprocket wheel 156. A pair of connected sprocket wheels 157 and 158 85 are mounted on an extension of the stud 31 upon which the arm 29 is mounted and the wheel 157 is driven from the wheel 156 by a connecting chain 159, while the wheel 158 drives the sprocket wheel 75 previously 90 referred to by a connecting chain 160.

The center rest.—The function of the rib 33^a of the rail 33 is to hold said rail relatively rigid, i. e. to prevent its springing under stresses, and thereby to insure that 95 all the saws shall be cut to uniform depth. To aid this result, it is also preferred to provide a center rest or support for the saw mandrel whose function is to prevent 100 said mandrel from springing during the operation of the cutters. This center rest (Figs. 24 to 27) is preferably of the construction shown and comprises a vertical arm 161 located in the rear and at the center of the gang of saws and pivoted at its 105 lower end to the bed or base of the machine. Said arm, which is preferably of channeled construction, is adjustable about its pivot and is held in any desired position by a rearwardly projecting bolt 162 pivoted to 110 the frame of the machine. The transverse wall of the arm has a vertical slot 163 through which the bolt extends and said bolt carries on its rear end an adjusting nut 164 acting on a spacer 165 which surrounds 115 said bolt between said nut and a washer 166 bearing against the rear face of said transverse wall. The arm 161 carries at its upper end a curved bearing jaw 167 which engages the center space block of the saw 120 mandrel and has a rearwardly projecting slotted shank 168. The arm is provided with a recess 169 in which said shank slides and with a retaining bolt 170 which passes 125 through the slot in said shank. The jaw 167 is adjusted and also held rigidly against backward movement relative to the arm 161 by a pair of stems 171 located above and below the shank 168 and threaded through bearing blocks 172 having end trunnions or 130

bearings in the side walls of said arm. Obviously the arm 161 and jaw 167 may be set to conform to variations in the diameters of the saws and the space blocks interposed between them.

Résumé of the operations of the machine.—The operation of the machine is commenced, with the parts in the relation shown diagrammatically in Fig. 28. The 10 cutters are fed inward by the co-action of the cams 51 with the rollers 53, forming notches in the saws in their inward movement, and are thereafter withdrawn to positions wherein their peripheries are just 15 beyond the peripheries of the saws, at which time the saws are rotated through the distance of a tooth by the saw feeding mechanism. These operations are repeated until 20 the work of the cutters has progressed throughout the peripheral extent of the saws, whereupon the quadrants 59 are operated in the manner explained. During the 25 movement of the quadrants 59, and while said quadrants are approximately in the positions shown in Fig. 29, the cutter heads are shifted laterally or transversely by the operation of the shifting head 102 and as 30 the quadrants 59 return to their normal position the cutter heads are moved thereby, into operating relation to the next succeeding saws in order that the cutters may operate upon such saws and upon the relatively 35 opposite faces of the saws upon which they previously operated. The operations of the cutters throughout the peripheral extent of the saws and the shifting of the cutters from one saw to another are repeated until all the saws of the gang have been completed, at which time the operation of the machine 40 is arrested (for example, by shifting the driving belt to a loose pulley), and the mandrel with the finished saws thereon is removed from the machine, the cross-rail 33 and therewith the cutter heads being first 45 turned outward and upward as previously disclosed. Upon the completion of the work on a gang of saws, the position of the lever 112 is reversed whereby the operation of the machine upon the next gang of saws 50 may be resumed without resetting the cutter heads, the cutters in such a case being shifted from saw to saw in a direction opposite to the direction in which they were 55 shifted during the preceding operation. The operation of the machine as above 60 described, is entirely automatic and, except for the removal and insertion of the saw gangs, does not require the presence of an attendant. The operation, moreover, proceeds with marked rapidity, the time required for completing a gang of saws, *i. e.* a normal linter gang containing one hundred and six saws being (where the machine embodies twenty-seven cutter heads, as 65 herein suggested), approximately half an

hour when the formed teeth are merely to be renewed, and an hour, more or less, when the teeth are to be newly cut in saw blanks or in formed saws of the types heretofore existing. The great economy which is 70 thereby effected will be appreciated when it is considered that the sharpening of the teeth of linter saws, daily necessary to insure good, or even fair, results in linting, consumes, as indifferently effected by the 75 ordinary filing and gumming machines, four or five hours during which the linter stands idle and the constant presence of an attendant at the filing and gumming machines is required; and that in consequence 80 of the great amount of time required for the work of sharpening, the saws are frequently neglected, or, at least, are not sharpened as often as necessary, with the result that the work of the linter is poor. A similar economy, as regards time and labor, is effected in the cutting of new teeth in saw blanks. Heretofore, the teeth have been punched and then sharpened by side filers, operations which for the completion of a 90 gang, require many hours of time and the constant presence of an attendant.

As regards the cutting of new teeth in saws of the types heretofore existing, the machine effects a marked and valuable saving in the intrinsic cost of the saws by rendering their useful life indefinite. The average life of the saws (which require a special grade of steel for their manufacture and are quite expensive), where, as heretofore, they are sharpened by the ordinary filing and gumming machines, is two months, more or less, after which they are 95 "scrapped". It follows that many old saws which would otherwise be thrown 100 away can be reclaimed and used for an extensive period by cutting new teeth therein with the machine of the present invention.

The invention is believed to be of considerable novelty and may, as is manifest, be 110 embodied in machines whose structural details will have pronounced variations. Therefore, although I have disclosed merely a single embodiment of the invention, it is to be understood that numerous modifications, falling within the scope of the 115 appended claims, may be resorted to.

In certain of the following claims, reference is made to the cutter heads or their supporting arms as being movable from and 120 back to their "normal" positions; and it may be explained that the word "normal" refers to the position from which the normal vibrating or reciprocatory movements of the cutter heads and their supporting arms is 125 initiated.

I claim as my invention—

1. In a machine for forming or renewing 130 gin or linter saw teeth, a bevel cutter rotatable in a plane transverse to the plane of

- the saw and positioned to operate on the stock of the saw at one side thereof whereby said cutter forms in the edge of the saw a notch having a face providing a tooth base and a laterally inclined opposing face, means 5 for rotating the cutter and means for advancing the cutter relatively to the saw while operating thereon and in a path parallel to the plane of the saw.
- 10 2. In a machine for forming or renewing gin or linter saw teeth, a bevel cutter rotatable in a plane transverse to the plane of the saws and positioned to operate simultaneously on the stock of two saws at adjacent sides thereof whereby said cutter forms in the edge of each saw a notch having a face providing a tooth base and a laterally inclined opposing face, means for rotating the cutter, and means for advancing the cutter relatively to the saws while operating thereon and in a path parallel to the planes of the saws.
- 15 3. In a machine for forming or renewing gin or linter saw teeth, in combination, a bevel cutter rotatable in a plane transverse to the planes of the saws and positioned to operate simultaneously on the stock of two saws at adjacent sides thereof whereby said cutter forms in the edge of each saw a notch 20 having a face providing a tooth base and a laterally inclined opposing face, a head by which said cutter is carried and which is provided with means for bracing said saws against lateral bending play, and means for 25 rotating the cutter.
- 30 4. In a machine for forming or renewing gin or linter saw teeth, in combination, a bevel cutter rotating in a plane transverse to the plane of the saw and positioned to operate on the stock of the saw at one side thereof whereby said cutter forms in the edge of the saw a notch having a face providing a tooth base and a laterally inclined opposing face, a head by which said cutter 35 is carried and which is provided with means for bracing said saw against lateral bending play, and means for rotating the cutter.
- 40 5. In a machine for forming or renewing linter saw teeth, a bevel cutter rotating in a plane transverse to the plane of the saw and positioned to operate on the stock of the saw at one side thereof whereby said cutter forms in the edge of the saw a notch having a transversely straight face and a laterally 45 inclined opposing face, means for rotating the cutter and means for advancing the cutter relatively to the saw while operating thereon and in a path parallel to the plane of the saw.
- 50 6. In a machine for forming or renewing gin or linter saw teeth, a cutter head comprising a casing, a spindle supported therein, and a rotatable cutter mounted on said spindle, said casing having its face provided 55 with a pair of slots or recesses into which a 65 pair of adjacent saws simultaneously acted upon by said cutter project, the walls of said slots or recesses bracing said saws against lateral bending play.
7. In a machine for forming or renewing 70 gin or linter saw teeth, a cutter head comprising a casing having a vertical bore and a recess intermediate said bore opening to one of its side faces, a spindle journaled in said bore and having an annular shoulder 75 and a reduced portion below said shoulder, a gear arranged in said recess and mounted on said reduced portion adjacent said shoulder, and a rotatable cutter mounted on the lower end of the said spindle. 80
8. In a machine for forming or renewing gin or linter saw teeth, in combination, a rotatable bevel cutter to operate on the stock of the saw, said cutter having its working plane transverse to the plane of the saw, 85 and means for positioning the cutter to operate first on one, and thereafter on the opposite, side of the saw.
9. In a machine for forming or renewing 90 gin or linter saw teeth, in combination, a cutter head comprising a casing, a spindle journaled therein and a rotatable cutter mounted on the spindle, a support on which the cutter head is slidably mounted, a gear mounted on the spindle, a companion driving gear having hub extensions, bearings carried by said cutter head casing in which said hub extensions are journaled, and a drive shaft for said driving gear extended 95 through the hub extensions thereof and for 100 which said driving gear provides intermediate support, said driving gear being slidable on its shaft and being movable with said cutter head as the latter is slid along its support. 105
10. In a machine for forming or renewing 110 gin or linter saw teeth, in combination, a cutter head comprising a casing, a spindle journaled therein and a rotatable cutter mounted on the spindle, a cross-rail on which the cutter head is slidably mounted, said cross-rail having cylindrical terminal extensions, a drive shaft parallel to the cross-rail and having its ends journaled in 115 said terminal extensions, a gear mounted on the spindle and a companion driving gear slidably mounted on said drive shaft, said driving gear being movable with said cutter head as the latter is slid along said cross-rail. 120
11. In a machine for forming or renewing 125 gin or linter saw teeth, in combination, a cutter head comprising a casing, a spindle journaled therein and a rotatable cutter mounted on the spindle, a cross-rail on which the cutter head is slidably mounted, said cross-rail having cylindrical terminal extensions, a drive shaft parallel to the cross-

- 5 rail and having its ends journaled in said terminal extensions, a gear mounted on the spindle, a companion driving gear having hub extensions and slidably mounted on said 10 drive shaft, and bearings for said hub extensions carried by said cutter head casing whereby said driving gear provides intermediate support for said drive shaft and is movable with said cutter head as the latter 15 is slid along said cross-rail.
12. In a machine for forming or renewing gin or linter saw teeth, in combination, a cross-rail, a cutter head arranged adjacent the inner face of the cross-rail and mounted 15 thereon for sliding movement lengthwise thereof, said cutter head having a rotatable cutter, and a drive shaft for said cutter, said cross-rail being formed to inclose said shaft and the latter extending from end to end 20 of said cross-rail.
13. In a machine for forming or renewing gin or linter saw teeth, in combination, a cross-rail having a C-shaped cross-section, a cutter head arranged adjacent the inner face 25 of said rail and mounted thereon for sliding movement lengthwise thereof, said cutter head having a rotatable spindle carrying a cutter and a gear, a drive shaft for the cutter and a gear mounted on said drive shaft 30 for coöperation with the gear of said cutter head, said drive shaft and the gear mounted thereon being inclosed within said cross-rail between the curved wall thereof and said cutter head.
14. In a machine for forming or renewing gin or linter saw teeth, in combination, a cross-rail having longitudinal ribs along its upper and lower edges, a cutter head mounted to slide on said cross-rail and having upper and lower grooves into which said ribs 40 project, and a gib associated with said cutter head and fitted in one of the grooves thereof against the cross-rail rib which projects into said groove.
15. In a machine for forming or renewing gin or linter saw teeth, in combination, a transversely movable cutter head, a cross-rail carrying said head, a pair of supporting arms having ends pivotally mounted, said 50 cross-rail being supported by said arms at their free ends, and means for normally vibrating said arms and therewith said cross-rail to effect reciprocatory movements of said cutter held in a plane perpendicular to its direction of transverse movement.
16. In a machine for forming or renewing gin or linter saw teeth, in combination, a cross-rail, a cutter head slidably mounted thereon, a pair of supporting arms pivotally 60 mounted at their lower ends, said cross-rail having its ends connected to the free upper ends of said arms for support thereby, and means for normally vibrating said arms and therewith said cross-rail to effect reciprocatory movements of said cutter head in a

plane perpendicular to its direction of sliding movement along said cross-rail.

17. In a machine for forming or renewing gin or linter saw teeth, in combination, a cross-rail, a pair of supporting arms having 70 ends pivotally mounted, said cross-rail having its ends secured in the free ends of said arms, a drive shaft parallel to said cross-rail and supported by said arms, a cutter head slidably mounted on said cross-rail, a 75 driving gear associated with said cutter head and driven by said shaft, said driving gear being movable lengthwise of said shaft and participating in the sliding movement of said cutter head, and means for normally 80 vibrating said arms and therewith said cross-rail to effect reciprocatory movements of said cutter head in a plane perpendicular to its direction of sliding movement along said cross-rail.

18. In a machine for forming or renewing gin or linter saw teeth, in combination, a transverse cutter head support, a pair of supporting arms having ends pivotally mounted and carrying said support at their 90 free ends, relatively stationary arms adjoining said supporting arms and cam devices co-acting between said supporting arms and relatively stationary arms for normally vibrating said supporting arms. 95

19. In a machine for forming or renewing gin or linter saw teeth, in combination, a transverse cutter head support, a pair of supporting arms pivotally mounted at their lower ends and carrying said support at their 100 free upper ends, said supporting arms tending to swing outward by gravity, relatively stationary arms adjoining said supporting arms and cam devices co-acting between said supporting arms and relatively stationary 105 arms for normally vibrating said supporting arms.

20. In a machine for forming or renewing gin or linter saw teeth, in combination, a transverse cutter head support, a pair of 110 supporting arms having ends pivotally mounted and carrying said support at their free ends, a drive shaft extending between and supported by said arms, cams operated by said drive shaft, and relatively stationary 115 arms adjoining said supporting arms and having rollers against which said cams operate.

21. In a machine for forming or renewing gin or linter saw teeth, in combination, 120 a transverse cutter head support, a pair of supporting arms pivotally mounted at their lower ends and carrying said support at their free upper ends, said supporting arms tending to swing outward by gravity, relatively stationary arms adjoining said supporting arms, a drive shaft extending between and supported by said supporting arms, a cam shaft also extending between 125 and supported by said supporting arms and 130

- geared to said drive shaft, cams on said cam shaft, and rollers on said relatively stationary arms against which said cams operate.
22. In a machine for forming or renewing gin or linter saw teeth, in combination, 5 a transverse cutter head support, a pair of supporting arms having ends pivotally mounted and carrying said support at their free ends, a pair of relatively stationary arms adjoining and pivoted co-axially with the respective supporting arms, cam devices operating between said supporting arms and said relatively stationary arms to normally vibrate said supporting arms, a third pair of 10 arms adjoining and pivoted co-axially with the respective supporting arms, and connections between said respective relatively stationary arms and said last-mentioned arms to support the former from the latter and to 15 provide for adjustments of the positions of said relatively stationary arms.
23. In a machine for forming or renewing gin or linter saw teeth, in combination, a transverse cutter head support, a pair of supporting arms having ends pivotally mounted and carrying said support at their free ends, means for normally vibrating said supporting arms about their pivots, and means acting periodically for moving said supporting 20 arms about their pivots from and back to their normal operative position.
24. In a machine for forming or renewing gin or linter saw teeth, in combination, a cutter head mounted for transverse movement, a support therefor, a pair of supporting arms having ends pivotally mounted and carrying said support at their free ends, means for normally vibrating said supporting arms about their pivots, means acting 25 periodically for moving said supporting arms about their pivots from and back to their normal operative position, and means for transversely moving said cutter head while the supporting arms are out of their 30 normal operative position.
25. In a machine for forming or renewing gin or linter saw teeth, in combination, a pair of pivotally mounted arms, means controlling their positions and periodically 35 operable to effect movements thereof from and back to their normal positions, a cutter head support, a pair of supporting arms pivoted co-axially with said first-named arms and carrying said support at their free ends, means for controlling the positions of said supporting arms and periodically operable to effect movements thereof from and back to their normal positions, a cutter head support, a pair of supporting arms pivoted co-axially with said first-named arms and carrying said support at their free ends, means movable with said first-named arms for controlling the positions of said supporting arms whereby said supporting arms participate in the movements of said first-named arms, means co-acting with said last-named means for normally vibrating said supporting arms about their pivots, and means for transversely moving said cutter head while the supporting arms are out of their normal operative position.
26. In a machine for forming or renewing gin or linter saw teeth, in combination, a cutter head, normally vibratory supporting means therefor, and means operable periodically for moving said supporting means from and back to its normal position.
27. In a machine for forming or renewing gin or linter saw teeth, in combination, a transversely shiftable cutter head, normally vibratory supporting means therefor and cutter head positioning means including means operable periodically for moving said supporting means from and back to its normal position and means for transversely shifting said cutter head during the operation of said periodically operable means.
28. In a machine for forming or renewing gin or linter saw teeth, in combination, a cutter head, normally vibratory supporting means therefor, saw feeding means operable in correlation to the vibratory movements of said supporting means, means operable periodically for moving said supporting means from and back to its normal position, and means operable by an element of said saw-feeding means for controlling the operations of said periodically operable means.
29. In a machine for forming or renewing gin or linter saw teeth, in combination, a transversely shiftable cutter head, nor-

5 mally vibratory supporting means therefor and cutter head positioning means including means operable periodically for moving said supporting means from and back to its normal position, means for transversely shifting said cutter head, and means operable in conjunction with the movement of said supporting means by said periodically operable means for controlling the operation of the means for transversely shifting the cutter head.

10 32. In a machine for forming or renewing gin or linter saw teeth, in combination, a transversely shiftable cutter head, normally vibratory supporting means therefor, saw feeding means operable in correlation to the vibratory movements of said supporting means, and cutter head positioning means including means operable periodically for moving said supporting means from and back to its normal position, means operable by an element of said saw-feeding means for controlling the operations of said periodically operable means, means for transversely shifting said cutter head and means operable in conjunction with the movement of said supporting means by said periodically operable means for controlling the operation of the means for transversely shifting the cutter head.

15 33. In a machine for forming or renewing gin or linter saw teeth, in combination, a cutter head, means for normally vibrating said cutter head, and means operable periodically for moving said cutter head from and back to its normal position.

20 34. In a machine for forming or renewing gin or linter saw teeth, in combination, a transversely shiftable cutter head, means for normally vibrating said cutter head and cutter head positioning means including means operable periodically for moving said cutter head from and back to its normal position and means for transversely shifting said cutter head during the operation of said periodically operable means.

25 35. In a machine for forming or renewing gin or linter saw teeth, in combination, a transversely shiftable cutter head, means for normally vibrating said cutter head and cutter head positioning means including means operable periodically for moving said cutter head from and back to its normal position, means for transversely shifting said cutter head during the operation of said periodically operable means and means for controlling the direction in which said cutter head is transversely shifted.

30 36. In a machine for forming or renewing gin or linter saw teeth, in combination, a normally vibratory cutter head, a pair of movably mounted arms operable to move said cutter head from and back to its normal position, saw feeding mechanism operated in correlation to the vibrations of said

35 cutter head and including a rotatable gear element, a normally stationary operating shaft for said arms, a rotating operating element for said shaft, a clutch for connecting said operating element and said shaft, means normally holding said clutch inoperative and operable to provide for and interrupt the operation of said clutch, and operative connections between said gear element and said means for operating said means at a fixed period in each revolution of said gear element to provide for the operation of said clutch.

40 37. In a machine for forming or renewing gin or linter saw teeth, in combination, a normally vibratory cutter head, a pair of movably mounted arms operable to move said cutter head from and back to its normal position, saw feeding mechanism operated in correlation to the vibrations of said cutter head and including a rotatable gear element, a normally stationary operating shaft for said arms, a rotating operating element for said shaft, a clutch for connecting said operating element and said shaft, a lever normally holding said clutch inoperative and operable to provide for and interrupt the operation of said clutch, an operating arm associated with said lever and having angularly disposed projections, a slidably and pivotally mounted spring supported plunger having an end formed to engage and to be engaged by said respective projections and a pin on said rotatable gear element for operating said plunger against the pressure of its supporting spring.

45 38. In a machine for forming or renewing gin or linter saw teeth, in combination, a normally vibratory cutter head, a pair of movably mounted arms operable to move said cutter head from and back to its normal position, saw feeding mechanism operated in correlation to the vibrations of said cutter head and including a rotatable gear element, a normally stationary operating shaft for said arms, a rotatable operating element for said shaft, a clutch for connecting said operating element and said shaft including a spring-urged connecting pin, a lever normally engaging said connecting pin to prevent an operation thereof and operable to release said pin and also to restore said pin to its normal operative position, and operative connections between said gear element and said lever for operating said lever to release said connecting pin at a fixed point in each revolution of said gear element.

50 39. In a machine for forming or renewing gin or linter saw teeth, in combination, a normally vibratory cutter head, a pair of movably mounted arms operable to move said cutter head from and back to its normal position, saw feeding mechanism operated in correlation to the vibrations of said

- cutter head, a normally stationary operating shaft for said arms, a rotating operating element for said shaft, a clutch for connecting said operating element and said shaft, 5 means self-acting to interrupt the operation of said clutch and to normally hold said clutch inoperative, said means being operable to provide for the operation of said clutch, and means associated with an ele- 10 ment of said saw feeding mechanism for operating said last-named means at a fixed period of the operation of the machine to provide for an operation of said clutch.
40. In a machine for forming or renewing gin or linter saw teeth, in combination, a normally vibratory cutter head mounted for transverse movement, means operating periodically for moving said cutter head to and from its normal position, normally in- 15 active means for transversely shifting said cutter head, a clutch controlling the operation of said last-named means, and means operable to provide for an operation of said clutch in conjunction with the movement of 20 said cutter head by said periodically operable means.
41. In a machine for forming or renewing gin or linter saw teeth, in combination, a normally vibratory cutter head mounted for transverse movement, supporting means therefor, a pair of arms periodically movable to move said supporting means from and back to its normal position, normally in- 25 active means for transversely shifting said cutter head, a clutch controlling the operation of said last-named means, a clutch controlling means including a trip arm carried by an element of said supporting means and a stationary block which engages and oper- 30 ates said trip arm as the supporting means approaches the limit of its outward movement.
42. In a machine for forming or renewing gin or linter saw teeth, in combination, a normally vibratory cutter head mounted for transverse movement, a supporting means therefor including a pair of supporting arms, means operating periodically for moving said supporting means and there- 35 with said cutter head from and back to its normal position, normally inactive means for transversely shifting said cutter head, a clutch controlling the operation of said last-named means and means for controlling said clutch including a rock shaft carried by one of said supporting arms, a clutch controlling arm carried by said rock shaft, a trip arm mounted on said rock shaft and a stationary block which engages and operates said trip arm as the supporting arms approach the limit of their outward movement.
43. In a machine for forming or renewing gin or linter saw teeth, in combination, a normally vibratory cutter head mounted 40 for transverse movement, supporting means therefor, means operating periodically for moving said supporting means and there- 45 with said cutter head from and back to its normal position, normally inactive means for transversely shifting said cutter head, a clutch controlling the operation of said last-named means and means for controlling said clutch, a pair of pivotally mounted arms carrying said cross-rail at their free ends, means operating periodically for moving said arms from and back to their normal positions, normally inactive means carried by said cross-rail for transversely shifting said cutter head, a continuously rotating shaft carried by one of said arms, gearing connecting said shaft and said normally inactive means and including a controlling clutch, a controlling arm normally preventing, and operable to provide for and interrupt, the operation of said clutch, and means operable in connection with the operation of said periodically operable means for operating said controlling arm to provide for an operation of said clutch.
44. In a machine for forming or renewing gin or linter saw teeth, in combination, a cross-rail, a cutter head mounted thereon for transverse shifting movement, a pair of pivotally mounted arms carrying said cross-rail at their free ends, means operating periodically for moving said arms from and back to their normal positions, normally inactive means carried by said cross-rail for transversely shifting said cutter head, a continuously rotating shaft carried by one of said arms, gearing connecting said shaft and said normally inactive means and including a controlling clutch, a controlling arm normally preventing, and operable to provide for and interrupt, the operation of said clutch, and means operable in connection with the operation of said periodically operable means for operating said controlling arm to provide for an operation of said clutch.
45. In a machine for forming or renewing gin or linter saw teeth, in combination, a cross-rail, a cutter head mounted thereon for transverse shifting movement, a pair of pivotally mounted arms carrying said cross-rail at their free ends, means operating periodically for moving said arms from and back to their normal positions, normally inactive means carried by said cross-rail for transversely shifting said cutter head, a continuously rotating shaft carried by one of said arms, gearing connecting said shaft and said normally inactive means and including a controlling clutch and means for controlling said clutch including a rock shaft carried by the supporting arm which carries said continuously rotating shaft, a clutch controlling arm mounted on said rock shaft, normally preventing and operable to provide for and interrupt the operation of said clutch, a trip arm mounted on said rock shaft and a stationary block which engages and operates said trip arm as the supporting arms approach the limit of their outward movement.
46. In a machine for forming or renewing gin or linter saw teeth, in combination, a transversely shiftable cutter head, means for normally vibrating the same, a pair of pivotally mounted arms periodically movable to move said cutter head from and back to its

normal position, eccentrics controlling the positions and movements of said arms, a normally stationary shaft for operating said eccentrics, a clutch controlling the operation of said shaft, saw feeding mechanism operable in correlation to the normal operative vibrations of said cutter head, means operated at regular periods by an element of said saw feeding mechanism for controlling the operation of said clutch to provide for the rotation of said shaft, normally inactive means for transversely shifting said cutter head, a clutch controlling the operation of said last-named means, and means operable in connection with the outward movement of said arms by said eccentrics for controlling the operation of said last-named clutch to provide for an operation of the means for transversely shifting the cutter head.

47. In a machine for forming or renewing gin or linter saw teeth, in combination, a cutter head mounted for transverse movement, a transversely reciprocatory shifting head, pawl and ratchet operative connections between said shifting head and said cutter head for transmitting the movement of said shifting head, in one direction, to said cutter head, and means for automatically and periodically moving said shifting head from and back to its normal position.

48. In a machine for forming or renewing gin or linter saw teeth, in combination, a cross-rail, a cutter head slidably mounted thereon for transverse movement, a transversely reciprocatory shifting head mounted thereon and pawl and ratchet operative connections between said shifting head and said cutter head for transmitting the movement of said shifting head, in one direction, to said cutter head.

49. In a machine for forming or renewing gin or linter saw teeth, in combination, a cross-rail, a cutter head slidably mounted thereon for transverse movement, a transversely reciprocatory shifting head mounted thereon, a rod to which said cutter head is made fast and which is provided with ratchet teeth and a pawl carried by said shifting head for engagement with said ratchet teeth.

50. In a machine for forming or renewing gin or linter saw teeth, in combination, a cross-rail, a cutter head slidably mounted thereon for transverse movement, a transversely reciprocatory shifting head mounted thereon, a rod to which said cutter head is made fast and which is provided with ratchet teeth and a reversible pawl carried by said shifting head for engagement with said ratchet teeth.

51. In a machine for forming or renewing gin or linter saw teeth, in combination, a cross-rail, a cutter head slidably mounted thereon for transverse movement, a trans-

versely reciprocatory shifting head mounted thereon, a rod to which said cutter head is made fast and which is provided with ratchet teeth, a pawl carried by said shifting head for engagement with said ratchet teeth, 70 a pair of pivotally mounted supporting arms carrying said cross-rail, and means for normally vibrating said arms.

52. In a machine for forming or renewing gin or linter saw teeth, in combination, a cutter head mounted for transverse movement, a transversely reciprocatory shifting head, a rod to which the cutter head is made fast, the shifting head having an opening through which said rod extends, a double toothed centrally pivoted reversible pawl carried by the shifting head, the rod having ratchet teeth for engagement by said pawl, a pawl adjusting lever carried by the shifting head, the pawl having a projection at 85 one side of its pivot and springs carried by said lever and engaging at opposite sides of said projection.

53. In a machine for forming or renewing gin or linter saw teeth, in combination, 90 a cutter head mounted for transverse movement, a transversely reciprocatory shifting head, pawl and ratchet operative connections between said shifting head and said cutter head for transmitting the movement of the shifting head, in one direction, to said cutter head, and a rotatable cylinder upon which the shifting head is slidably mounted and which forms a companion element of the shifting head, one of said companion elements having a cam groove and the other having a projection which engages in said groove.

54. In a machine for forming or renewing gin or linter saw teeth, in combination, a cross-rail having a cylindrical portion, a cutter head slidably mounted on said cross-rail for transverse movement, a cam rotatably mounted on the cylindrical portion of said cross-rail, a transversely reciprocatory shifting head operated by said cam and pawl and ratchet operative connections between said shifting head and said cutter head for transmitting the movement of the shifting head, in one direction, to the cutter 115 head.

55. In a machine for forming or renewing gin or linter saw teeth, in combination, a cross-rail having a cylindrical portion, a cutter head slidably mounted on said cross-rail for transverse movement, a cylinder rotatably mounted on the cylindrical portion of the cross-rail, a transversely reciprocatory shifting head slidably mounted upon said cylinder, and pawl and ratchet operative 125 connections between said shifting head and said cutter head for transmitting the movement of the shifting head, in one direction, to the cutter head, said shifting head and said cylinder forming companion elements, 130

one of which is provided with a cam groove and the other of which is provided with a projection engaging in said groove.

56. In a machine for forming or renewing gin or linter saw teeth, in combination, a cross-rail having a cylindrical portion, a cutter head slidably mounted on said cross-rail for transverse movement, a cylinder rotatably mounted on the cylindrical portion 10 of the cross-rail, a transversely reciprocatory shifting head slidably mounted upon said cylinder, said shifting head and said cylinder forming companion elements, one of which is provided with a cam groove and 15 the other of which is provided with a projection engaging in said groove, a rod to which the cutter head is made fast, the shifting head having an opening through which the rod extends and the rod being provided 20 with ratchet teeth, and a pawl carried by the shifting head for engagement with said ratchet teeth.

57. In a machine for forming or renewing gin or linter saw teeth, in combination, a 25 cross-rail having cylindrical terminal extensions, a pair of supporting arms having clamp boxes in which said extensions are secured, said cross-rail having a shoulder adjacent one of said extensions, a cutter head 30 slidably mounted on said cross-rail beyond said shoulder for transverse movement, a sleeve rotatably mounted on the terminal portion which said shoulder adjoins with its ends closely adjacent said shoulder and the 35 adjacent supporting arm, a gear secured on the end of said sleeve adjacent said supporting arm, a transversely reciprocatory shifting head slidably mounted on the other end of said sleeve, a cam for reciprocating said 40 shifting head consequent to the rotation of said sleeve and pawl and ratchet operative connections between said shifting head and said cutter head whereby the movement of the shifting head is transmitted, in one direction, to the cutter head.

58. In a machine for forming or renewing gin or linter saw teeth, in combination, a cross-rail, a cutter head mounted thereon, a pair of pivotally mounted supporting arms 50 carrying the cross-rail, a cam shaft supported by said arms, saw feeding mechanism, a cam on said cam shaft for operating said saw feeding mechanism, other cams on said cam shaft, and relatively stationary devices against which said last-named cams 55 operate to normally vibrate said supporting arms.

59. In a machine for forming or renewing gin or linter saw teeth, in combination, a cross-rail, a cutter head mounted thereon, a pair of pivotally mounted supporting arms carrying said cross-rail, a cam shaft supported by said arms, saw feeding mechanism including a ratchet wheel and an operating lever having a pawl for engagement 65

with said ratchet wheel, said lever projecting across said cam shaft, and a cam on said cam shaft for engagement with said lever.

60. In a machine for forming or renewing gin or linter saw teeth, in combination, a 70 cutter head, means for normally vibrating the same, a pair of arms controlling the position of said cutter head and periodically movable to move said cutter head from and back to its normal position, means for operating said arms in their periodic movements, saw feeding mechanism including a ratchet wheel and a lever having a pawl for engagement with said ratchet wheel, and means whereby said lever is rendered inoperative relatively to said ratchet wheel during said periodic movement of said arms. 75

61. In a machine for forming or renewing gin or linter saw teeth, in combination, a 80 cutter head, means for normally vibrating the same, a pair of arms controlling the position of said cutter head and periodically movable to move said cutter head from and back to its normal position, means for operating said arms in their periodic movements, saw feeding mechanism including a 85 ratchet wheel and a lever having a pawl for engagement with said ratchet wheel, and means whereby said arms on their movement from their normal position effect the disengagement of said pawl from said ratchet wheel and on their return movement establish the engagement of said pawl with said ratchet wheel. 90

62. In a machine for forming or renewing 100 gin or linter saw teeth, in combination, a cross-rail, a cutter head mounted thereon, a pair of pivotally mounted arms carrying said cross-rail, a drive shaft carried by said arms for operating the cutter of said cutter head, a cam shaft carried by said arms, saw feeding mechanism, a cam on said cam shaft operating said saw feeding mechanism, other cams on said cam shaft, relatively stationary elements against which said 105 last-named cams operate to effect vibratory movements of said arms, and gearing supported by one of said arms whereby said cam shaft is driven from said first-named shaft. 110

63. In a machine for forming or renewing 115 gin or linter saw teeth, in combination, a cutter head mounted for transverse movement, means for moving said cutter head from and back to its normal position, means for automatically and periodically operating said cutter head moving means, means for shifting said cutter head transversely while it is out of its normal position, means for automatically correlating the operations of 120 said cutter head moving means and said cutter head shifting means, and means for normally vibrating said cutter head. 125

64. In a machine for forming or renewing 130 gin or linter saw teeth, in combination, a

- cutter head mounted for transverse movement, means for moving said cutter head from and back to its normal position, means for automatically and periodically operating 5 said cutter head moving means, means for shifting said cutter head transversely while it is out of its normal position, means for automatically correlating the operations of said cutter head moving means and said cutter 10 head shifting means, and means for controlling the direction in which said cutter head is moved transversely by said means for shifting the same.
65. In a machine for forming or renewing 15 gin or linter saw teeth, in combination, a plurality of cutter heads mounted for transverse movement, means for normally and simultaneously vibrating said cutter heads, means operable automatically and periodically 20 for shifting said cutter heads simultaneously and transversely, and means for controlling the direction in which said cutter heads are simultaneously shifted by said last-named means.
- 25 66. In a machine for forming or renewing gin or linter saw teeth, in combination, a pair of pivotally mounted arms, a cross-rail carried thereby, a cutter head mounted for transverse movement on said cross-rail, and 30 means for effecting normal vibrations of said cutter head about the pivots of said arms as a center.
67. In a machine for forming or renewing 35 gin or linter saw teeth, in combination, a pair of pivotally mounted arms, a cross-rail carried thereby, a cutter head mounted for transverse movement on said cross-rail and having a rotatable cutter, means for effecting 40 normal vibrations of said cutter head about the pivots of said arms as a center, and means for rotating said cutter during the vibratory movements of said head.
68. In a machine for forming or renewing 45 gin or linter saw teeth, in combination, end supports for a gang of saws, and a rest for

bracing the saw gang intermediate its ends.

69. In a machine for forming or renewing 50 gin or linter saw teeth, in combination, end supports for a gang of saws, means for fashioning or renewing the teeth of the saws, and a rest for bracing the saw gang intermediate 55 its ends against the stresses developed by the action of said means.

70. In a machine for forming or renewing 60 gin or linter saw teeth, in combination, end supports for a gang of saws, and a rest for bracing the saw gang intermediate its ends, the said rest having an adjustable part to engage a space block intermediate a pair of adjacent saws.

71. In a machine for forming or renewing 65 gin or linter saw teeth, in combination, end supports for a gang of saws and a rest for bracing the saw gang intermediate its ends comprising an upright arm pivoted at its lower end for movement toward or from the saw gang, a support for the arm permitting adjustment thereof, and a jaw adjustably mounted at the upper end of the arm to engage a space block intermediate a pair of 70 adjacent saws.

72. In a machine for forming or renewing 75 gin or linter saw teeth, in combination, a rail disposed transversely of the gang of saws and having end trunnions, supports in which said trunnions are mounted whereby said rail may be turned about an axis disposed longitudinally thereof, a head mounted on and movable with said rail when the latter is turned, and a rotatable cutter 80 mounted at one end of said rail for acting on the stock of the saws to fashion or renew the teeth thereof.

In testimony whereof I have hereunto set my hand in presence of two subscribing witnesses.

ROBERT H. BUTTERS.

Witnesses:

CLIFF C. HATCHER,
REX B. MOONEY.
